UNITED STATES PATENT OFFICE.

OTTO THURMANN, OF BERLIN, GERMANY.

COCOA AND CHOCOLATE GRINDER.

Application filed May 10, 1924, Serial No. 712,196, and in Germany February 6, 1924.

Known cocoa and chocolate grinders, comprising two horizontal grindstones (the upper one of which is rotary) do not grind the material to a satisfactory degree of fineness, even if the said material is ground in several successive stages. This disadvantage arises when the cocoa is very highly divided, in which condition it cannot be treated even on ordinary roller grinders.

10 This invention relates to a one-stage cocoa grinder with an upper rotary grindstone combined in one casing with a multiple roller grinder or a multiple ball grinder. The rollers or the balls rotate in the ground material and subject the latter to a most efficient treatment. The said material is thus ground to the required degree of fineness.

Three constructional examples of the grinder according to the present invention 20 are illustrated in the accompanying drawings in which—

Figures 1 and 2 illustrate one construction,

Figures 3 and 4 illustrate a second construction, and

Figures 5 and 6 illustrate a third construction.

Figures 1, 3 and 5 are vertical axial sections and Figures 2, 4 and 6 are plan views 30 with portions of the casing broken away.

Referring to Figures 1 and 2, the grinder comprises a stationary grindstone *a*, an upper rotary grindstone *b* mounted on and rotated by a spindle *c* in the usual way.

35 The outer periphery of a casing *g* of the rotary grindstone forms a grinding surface of a roller grinder. Rollers *l* are vertically mounted in an annular housing *m* in one piece with a casing *d* of the lower or stationary grindstone. The trunnions of the rollers are mounted in slots *n* obliquely positioned relatively to the radius of the grinder. The finished ground material leaves the housing *m* through holes *o*. It drops on a

45 collector *i* and leaves the grinder through a chute or spout *k*. The material is fed to the grinder in the usual way, the said grinder being heated according to any desired method. The material leaves the space between the two grindstones and directly enters the housing *m* in which the rollers *l* are located. The housing is filled with the material to the level of the holes *o* and is ground to the desired degree of fineness be-

50 tween the face of the rollers and the cylindrical grinding surface of the casing *g*.

The rollers are pressed against the grinding surface of the casing *g* because the upper grindstone is rotating in the direction of the arrow and also because the slots *o* are obliquely positioned.

55 In the construction illustrated in Figures 3 and 4, a grinding surface *p* of the casing *g* is in the form of an inverted cone and in contradistinction to the arrangement shown in Figures 1 and 2, the cylindrical rollers are stationary, that is to say non-movably mounted so that their axes are parallel to the generatrix of the conical grinding surface *p*. The required pressure between the 60 grinding surface is produced by the weight of the top portion or rotary grindstone. The grinding surface *p* being conical and the rollers *l* cylindrical, the grinding surfaces do not merely roll over each other, but 65 a certain amount of slip takes place between the said two surfaces. A particularly effective grinding action is derived from this circumstance and the material is ground extremely fine.

70 Referring to the construction illustrated in Figures 5 and 6, a ball grinder is combined with the grindstones. The casing *d* containing the lower grindstone *a* has an 75 annular race *e* of semi-circular cross-section to receive a large number of balls *f* adapted to roll around the axis of the grinder. The cover or casing *g* of the rotary grindstone has likewise an annular race *h* of semi-circular cross-section the concave face of which 80 faces downwards. The said race lies above the race *e* and covers the balls with which it is in contact so that when the grindstone *b* and the casing *g* are rotated, the balls are caused to roll in the race around the grindstone. The balls do not only have a rolling motion, but since they roll straight ahead, there is a certain amount of slip in the races 85 *e* and *h*. The race *e* is surrounded by the collector *i*.

100 The material leaves the space between the two grindstones and enters the race *e* directly, in which it is compressed and ground by the upper and lower zone of the balls. The material is thus ground to an extreme 105 degree of fineness.

Having now particularly described and ascertained the nature of my said invention and in what manner the same is to be performed, I declare that what I claim is:

110 1. In a cocoa mill, the combination of a pair of horizontally disposed grinding mem-

- 2
 bers in juxtaposition to each other, one of said members being stationary and the other rotatable, a pair of complementary housings enclosing said grinding members, the housing of the rotatable member being rotatable with said member, an annular chamber carried by the housing of the stationary member, said chamber being in communication with the interior of said housings, a plurality of grinding elements disposed within said chamber and adapted to rotate in contact with a portion of the wall of the rotatable housing, means for feeding material to be ground to the center of the horizontal grinding members, and means for delivering the ground material at the periphery of said annular chamber.
3. In a cocoa mill, the combination of a pair of horizontally disposed grinding members in juxtaposition to each other, one of said members being stationary and the other rotatable, a pair of complementary housings enclosing said grinding members, the housing of the rotatable member being rotatable with said member, an annular chamber carried by the housing of the stationary member, said chamber being in communication with the interior of said housings, the walls of said chamber being provided with slots extending at an angle to the radius of the chamber, a plurality of rotatable rollers journaled in said slots and adapted to rotate in contact with a portion of the wall of the rotatable housing, means for feeding material to be ground to the center of the horizontal grinding members, and means for delivering the ground material at the periphery of said annular chamber.
4. In a cocoa mill, the combination of a pair of horizontally disposed grinding members in juxtaposition to each other, one of
- said members being stationary and the other rotatable, a pair of complementary housings enclosing said grinding members, the housing of the rotatable member being rotatable with said member, an annular chamber of rectangular cross-section carried by the housing of the stationary member, said chamber being in communication with the interior of said housings, a plurality of rotatable rollers journaled in the walls of said chamber and having their axes inclined relatively to the horizontal grinding members, said rollers being adapted to rotate in contact with a portion of the wall of the rotatable housing, means for feeding material to be ground to the center of the horizontal grinding members, and means for delivering the ground material at the periphery of said annular chamber.
5. In a cocoa grinding mill, the combination of a middle grinder, comprising a stationary stone bottom and an upper mulling stone set in a rotatory housing, having several rolling grinding bodies disposed in a ring-shaped groove surrounding the stone bottom concentrically, and which bodies roll in contact with the outer surface of the mullingstone housing, the arrangement being such that the liquid material being ground passes from the middle grinder into the surrounding circular groove and there rises to such a height that the rolling grinding bodies run immersed for the greater part of their height in the grinding mash and the mash that is ground to the finest flows off from the surface and from the outer rim of the circular groove through outlet openings provided therefor.

In testimony whereof I affix my signature.

OTTO THURMANN.
